FUEL-CONTROL DEVICE FOR ENGINES

Application filed August 5, 1929. Serial No. 383,750.

My invention relates to and has for a purpose the provision of a device which in its association with the engine of a motor vehicle for example, is operable to discontinue the supply of fuel to the carburetor of the engine in the event that the lubricant circulating pump of the engine ceases operation or fails either as a result of lack of lubricant, clogged oil lines between the device and pump, or from other causes, to circulate sufficient lubricant to prevent damage to the working parts of the engine, thus insuring that the engine will cease operation should its lubricating system fail to function properly, and thereby positively preventing damage to the working parts of the engine from lack of lubricant.

It is another purpose of my invention to provide a fuel control device of the above described character to supply a quantity of fuel to the carburetor of the engine after the engine has ceased operating as a result of the device functioning to discontinue the supply of fuel so as to permit operation of the engine despite lack of lubrication, should it be necessary that the vehicle be driven under its own power to a place where inspection and repairs can be made, or the engine operated for any other reason.

I will describe only one form of fuel control device for engines embodying my invention and will then point out the novel features thereof in claims.

In the accompanying drawing,

Figure 1 is a view showing in side elevation one form of fuel control device embodying my invention, applied to an engine.

Figure 2 is an enlarged vertical sectional view of the fuel control device and illustrating the positions occupied by the moving parts thereof when the engine with which the device is associated, is in operation.

Figure 3 is a view similar to Figure 2 and illustrating the positions occupied by the moving parts of the device when operation of the engine has ceased, and

Figure 4 is a horizontal sectional view taken on the line line 4—4 of Figure 2 and looking in the direction of the arrows.

Referring specifically to the drawings in

which similar reference characters designate similar parts in each of the several views, my invention in its present embodiment comprises a substantially rectangular shaped body B formed of metal and having its upper portion hollow to provide a chamber 10 having an inlet 11 in its top wall which in the association of the fuel control device with the engine E of a motor vehicle, is connected to a pipe 12 leading from the vacuum tank (not shown) of the vehicle's fuel system or from a suitable source of supply on the vehicle so that fuel will be free to flow into the chamber prior to its delivery to the carburetor C of the engine. The bottom wall of the chamber 10 is provided with a pair of outlets 13 and 14 controlled by valves 15 and 16 respectively, and in the present instance the outlets 13 and 14 are formed to provide annular and beveled valve seats 17 and 18 respectively, for the valves, which latter are in the shape of beveled disks.

The valve 15 is provided with a stem 19 slidably mounted in a spider 20 supported in a cylindrical passage 21 leading from the outlet 13; and the valve is normally urged to close the outlet by means of a coil spring 22 surrounding the stem 19 and interposed between the spider and a piston 23 fixedly secured to the stem in any suitable manner. The piston works in a cylinder 24 forming a continuation of the lower end of the passage 21 and is of slightly larger diameter than the latter to produce an annular shoulder 25 against which the piston is adapted to abut when moved against the action of the spring 22 to the extreme position shown in Figure 2 so as to definitely limit the open position of the valve 15. Into the open lower end of the cylinder 24 is threaded a tubular plug 26 to which is connected a pipe 27 branching from the pressure line of the oil pump O of the engine.

The valve 16 is provided with a stem 28 extending freely through a second cylindrical passage 29 formed in the body in spaced parallel relation to the cylindrical passage 21. The stem 28 extends into a second cylinder 30 formed in the body B below the pas-

sage 29 and separated from the latter by a partition 31 through which the stem extends. To the stem 28 is secured, in any suitable manner, a second piston 32 which works in the cylinder 30; and the valve 16 is normally urged to the open position shown in Figure 3 by means of a coil spring 33 surrounding the stem 28 and interposed between the valve and the partition 31.

10 Into the open lower end of the cylinder 30 is threaded a tubular plug 34 to which is connected a pipe 35 leading to the intake manifold I of the engine E, and from the 15 passages 21 and 29 extend laterally, ducts 36 and 37 respectively, which communicate with a duct 38 into the end of which is connected a pipe 39 leading to the carburetor C of the engine. The top wall of the chamber 10 is provided with a pair of screw plugs 40 and 41, which when removed permit access 20 to the chamber in order to assemble the valves 15 and 16 in the body B, and the body when applied to the engine can be either supported in the location shown in Figure 25 1 by the various pipes connected to the body or in any other suitable manner.

The operation of the device is as follows: Let it be assumed that the engine E is in 30 operation and that the oil pump O is functioning properly to develop the pressure necessary to circulate the required amount of oil in the engine. The pressure developed by the oil pump will act through the pipe 27 and cylinder 24 on the piston 23 to move 35 the latter and hence the valve 15, to the position shown in Figure 2 wherein the valve 15 is opened against the action of its spring 22, whereas the suction created in the intake manifold I when the engine is in operation 40 will act through the pipe 35 and cylinder 30 to draw the piston 32 to the position shown in this figure wherein the valve 16 is closed against the action of its spring 33, so 45 that fuel from the source of supply will be free to flow from the chamber 10 through the outlet 13, passage 21, duct 36, duct 38, and pipe 39 to the carburetor C.

However, should the oil pump O cease 50 operation or for any reason fail to develop the necessary pressure to circulate the oil, the piston 23 with the valve 15 will be moved under the action of the spring 22 to the position shown in Figure 3 wherein the valve 15 closes the outlet 13 so as to discontinue the supply of fuel to the carburetor C. When the fuel in the carburetor has been 55 consumed, the engine will naturally cease operation; and when the engine has ceased operating, the absence of suction in the intake manifold I will render the spring 33 free to move the piston 32 with the valve 16 to the position shown in Figure 3 wherein the outlet 14 is opened so as to permit fuel to flow from the chamber 10, through the outlet 14, passage 29, duct 37, duct 38 and

pipe 39 to the carburetor C and thus refill the latter.

The valve 15, although closed, will thus be rendered ineffective to prevent the supply of fuel to the carburetor when the operation of the engine ceases following failure of the lubricating system to function properly, so that the engine can be operated despite the lack of proper lubrication, in order to permit the vehicle to be driven under its own power 70 should facilities not be close at hand to inspect and repair the lubricating system. However, when the engine is again started, the suction in its intake manifold I will effect closing of the valve 16 so that the engine will only operate until the amount of fuel supplied to the carburetor C, as a result of the previous opening of the valve 16, has been consumed, upon which the engine will again cease operation and the valve 16 will 75 again be free to open and permit an additional quantity of fuel to be supplied to the carburetor. The operation of the engine can thus be continued indefinitely if necessary, despite the fact that the valve 15 remains closed as a result of failure of the lubricating system. The operator will, however, be reminded and warned at relatively 80 short intervals by the stopping of the engine and the necessity for restarting it, that the continued operation of the engine under such conditions will ultimately result in damage to its working parts as a result of the lack of proper lubrication. 85

Although I have herein shown and described only one form of fuel control device for engines embodying my invention, it is to be understood that various changes and modifications may be made therein without departing from the spirit of the invention and the spirit and scope of the appended claims. 90

I claim:

1. In combination with an engine having a lubricant circulating pump, and means for supplying fuel to the carburetor, means for discontinuing the supply of fuel to the engine when said pump fails to circulate sufficient lubricant to prevent damage to the working parts of the engine, and thereby cause the engine to cease operation, and automatic means for rendering the last means ineffective to discontinue the supply of fuel to the engine when operation of the engine has ceased so that the engine will again be supplied with fuel for subsequent operation. 100

2. In combination with an engine having a lubricant circulating pump, and means for supplying fuel to the engine, means for discontinuing the supply of fuel to the engine when said pump fails to circulate sufficient lubricant to prevent damage to the working parts of the engine, and thereby cause the engine to cease operation, and means responsive to the absence of engine suction when the engine ceases operation for permitting fuel 105

to be supplied to the engine for subsequent operation of the engine.

3. In combination with an engine having a lubricant circulating pump, and means for supplying fuel to the engine, means for discontinuing the supply of fuel to the engine when said pump fails to circulate sufficient lubricant to prevent damage to the working parts of the engine, and thereby cause the engine to cease operation, and automatic means for permitting fuel to be supplied to the engine when operation of the engine has ceased.

4. A fuel control device for engines comprising means for discontinuing the supply of fuel to an engine when a pump for circulating lubricant to the working parts of the engine fails to circulate sufficient lubricant to prevent damage to the working parts, and automatic means for rendering the first means ineffective to discontinue the supplying of fuel to the engine when operation of the engine has ceased, so as to again permit fuel to be supplied to the engine.

5. A fuel control device for engines comprising means for discontinuing the supply of fuel to an engine when a pump for circulating lubricant to the working parts of the engine fails to circulate sufficient lubricant to prevent damage to the working parts, and means responsive to the absence of engine suction when the engine ceases operation, for rendering the first means ineffective to discontinue the supply of fuel to the engine when operation of the engine has ceased so as to again permit fuel to be supplied to the engine for subsequent operation.

6. A fuel control device for engines comprising means for discontinuing the supply of fuel to an engine when the pump for circulating lubricant to the working parts of the engine fails to circulate sufficient lubricant to prevent damage to the working parts, means normally acting to permit the supply of fuel to the engine, and means for preventing the last means from acting so long as the engine is operating so that when the engine ceases operation the last means will be free to permit fuel to be supplied to the engine for subsequent operation.

7. A fuel control device for engines comprising means for discontinuing the supply of fuel to an engine when a pump for circulating lubricant to the working parts of the engine fails to circulate sufficient lubricant to prevent damage to the working parts, means normally acting to permit the supply of fuel to the engine, and means responsive to suction created by the engine when in operation for preventing the last means from acting, so that when operation of the engine ceases, the last means will be free to permit fuel to be supplied to the engine for subsequent operation.

8. A fuel control device for engines com-

prising a chamber having an inlet adapted for connection to a source of fuel supply, and a pair of outlets adapted for connection to a carburetor, valves for controlling the outlets, one of which is normally urged to closed position and the other to open position, means responsive to pressure developed by the lubricant circulating pump of an engine for maintaining said one of the valves open so long as said pump circulates sufficient lubricant to prevent damage to the working parts of the engine, and means responsive to the action of suction created by the engine when in operation for maintaining said other of the valves closed so long as the engine is operating.

9. A fuel control device for engines comprising a chamber having an inlet adapted for connection to a source of fuel supply, and a pair of outlets adapted for connection to a carburetor, valves for controlling the outlets, one of which is normally urged to closed position and the other to open position, a cylinder adapted for connection to the lubricant circulating pump of an engine, a piston in the cylinder operatively connected to said one of the valves and operable by pressure of said pump to maintain said one of the valves open, a second cylinder adapted for connection to the intake manifold of the engine, and a piston in the second cylinder operatively connected to said other of the valves and operable by suction created in the intake manifold when the engine is in operation to maintain said other of the valves closed.

10. A fuel control device for engines comprising means for discontinuing the supply of fuel to an engine when a pump for circulating lubricant to the working parts of the engine fails to circulate sufficient lubricant to prevent damage to the working parts, and automatic means for supplying fuel to the engine when the engine ceases to operate as a result of functioning of the first means, so as to permit further operation of the engine.

11. A fuel control device for engines comprising means for discontinuing the supply of fuel to an engine when a pump for circulating lubricant to the working parts of the engine fails to circulate sufficient lubricant to prevent damage to the working parts, and means responsive to the absence of the suction of the engine when the latter ceases to operate as a result of functioning of the first means, for supplying fuel to the engine so as to permit further operation of the latter.
